FIG. 1

INVENTOR
FRED J. BOWMAN
By *Fay, Oberlin & Fay*
ATTORNEYS.

UNITED STATES PATENT OFFICE.

FREDERICK J. BOWMAN, OF CLEVELAND, OHIO, ASSIGNOR TO THE GRASSELLI CHEMICAL COMPANY, OF CLEVELAND, OHIO, A CORPORATION OF OHIO.

FURNACE.

1,235,003.

Specification of Letters Patent. Patented July 31, 1917.

Application filed November 10, 1916. Serial No. 130,529.

To all whom it may concern:

Be it known that I, FREDERICK J. BOWMAN, a citizen of the United States, and a resident of Cleveland, county of Cuyahoga, 5 and State of Ohio, have invented a new and useful Improvement in Furnaces, of which the following is a specification, the principle of the invention being herein explained and the best mode in which I have contemplated applying that principle, so as to distinguish it from other inventions.

The present invention, relating as indicated to furnaces, is of more particular interest in connection with a furnace for roasting or refining zinc ore and particularly zinc sulfid, which has to be roasted to drive off sulfur in the form of sulfur dioxid gas. In furnaces used for this purpose the ore is usually fed in to the uppermost of a number 15 of parallel horizontal chambers which are connected with each other, and through which the ore passes from top to bottom. During this passage of the ore it is heated by means of hot gases passing between and 20 around the various parallel horizontal chambers.

The present invention has particular reference to the connections between these chambers, being designed to provide a means 30 for permitting a free flow of material from one chamber to another without obstructing the passage of the sulfur dioxid gas which is evolved from the ore. To the accomplishment of the foregoing and related ends, said 35 invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

45 Figure 1 is a central longitudinal section in a furnace embodying my new invention, and Fig. 2 is an enlarged view also in section, showing one of the connections between two parallel chambers.

50 In Fig. 1, there is shown a furnace of well-known type which is used for roasting zinc or other ore, this furnace consisting of a plurality of horizontal and parallel roasting chambers 1. The lower chambers of this 55 series are inclosed and heated by means of

fire flues 2 which are connected to a suitable source of supply and which serve to maintain a roasting temperature in these lower chambers. The upper chambers are maintained at approximately the same temperature, although they are not surrounded and separated by means of these hot air ducts. Each of the chambers 1 is provided with an opening 3 at each end; this opening being normally closed by means of a pivoted door 4, which is capable of being lifted, and which serves for the introduction of a long rake or pushing member, which, when moved through the chamber from end to end serves to force the material therein along the bottom of the chamber and into a passage connecting that chamber with the one below it. I have devised an improved means of feeding the ore into the uppermost chamber 1, this means consisting of a hopper 5 of relatively large size connected by means of a straight vertical chute 6 with one end of the chamber 1. The roof of this chamber 1 is thickened beneath the hopper 5 and on each side of the chute 6, thus providing a relatively narrow passage into which the ore is fed. With an inlet chute of this type it is possible to push the material along the bottom of this chamber without difficulty and without the rake or bar riding over the 80 pile of material at the inlet end of the chamber, as is the case in furnaces having inlet chutes of the usual type.

In Fig. 2 I have shown an improved connection between the chambers, this connection consisting of a diagonal chute or opening 7, extending from one end of the upper chamber diagonally toward the center of the chamber below it. The left wall of this opening 7 is formed of one or more blocks of 90 refractory material, and is very much thicker than the bottom of the chambers 1, and thus serves to form a deflecting arch against which the ore falling through this opening will pile up. In this way the end of each 95 chamber 1 is effectively sealed against the introduction of the air or the escape of sulfur dioxid gas. Furthermore it is possible to introduce a rake or push member through one of the doors 4 and push the material on the bottom of one of these chambers toward the discharge end without breaking the seal about the end through which the rake is introduced for more than a second or two. As soon as the material below the blocks 7 100

110

is moved along in the chamber the material lying against the side of these blocks drops and forms a new mound of sufficient height to meet the bottom of these blocks 8 and 5 thus seal up this end of the chamber again.

It has been found that the present furnace operates very satisfactorily, without permitting the formation of "pockets" in the chambers and without the loss of any appreciable amount of the material.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

20 1. In a furnace of the character described the combination of two horizontal spaced chambers, a conduit connecting such chambers and disposed at an acute angle to each, and a deflecting arch member extending into the lower of said two chambers and forming the lower wall of said conduit, said arch member forming a surface against which the descending material may form a pile to seal such chamber at that point.

25 2. In a furnace of the character described the combination of two horizontal parallel

spaced chambers, a conduit extending diagonally from a point adjacent to one end of the upper chamber to the adjacent end of the lower chamber, and a deflecting arch member extending into said lower chamber and forming the lower wall of said conduit, said member also lying on the side of said conduit adjacent to the ends of said lower chamber and constituting a wall against 40 which the ore will pyramid and seal said chamber.

3. In a furnace of the character described, the combination of a plurality of parallel horizontal chambers connected in series by 45 diagonal passages extending from one end of a chamber to the adjacent end of the next lower chamber, and deflecting arch members extending downwardly from the roof of said chamber and disposed to form the lower 50 end of each at such passages, said members extending into such chambers to form a wall against which ore may pyramid and seal said chamber.

4. In a furnace of the character described, 55 the combination of a horizontal chamber, an ore supply passage extending vertically into said chamber, and deflecting arches forming the lower portion of such passage.

Signed by me, this 6th day of November, 60
1916.

FRED J. BOWMAN.
